**HOUSING FOR SCIENTIFIC INSTRUMENTS SUCH
AS A PHOTOMETER OR THE LIKE**

Thorleif H. Petterson, Pasadena, Calif., assignor to Beck-
man Instruments, Inc., Fullerton, Calif., a corporation
of California

Application May 23, 1955, Serial No. 36,172

Term of patent 14 years

(Cl. D26—1)

FIG. 1.

FIG. 2.

Fig. 1 is a perspective view of a housing for scientific instruments such as a photometer or the like embodying my new design showing the front thereof; and

Fig. 2 is a perspective view of the embodiment of Fig. 1 showing the rear thereof.

I claim:

The ornamental design for a housing for scientific instruments such as a photometer or the like, substantially as shown.
